UNITED STATES PATENT OFFICE.

JAMES A. CARSON, OF ILLAHEE, WASHINGTON.

WINDSHIELD WIPER.

Application filed March 16, 1926. Serial No. 95,014.

My invention relates to means employed for wiping the surface of glass in windows and the like and has been especially designed for wiping rain and moisture from wind-
5 shield glass.

The object of my invention is to provide a mechanism which will effectively handle a swipe bar for such purposes and one which is of a cheap, dependable, and durable construction.
10

A further object of my invention is to provide a swipe handling mechanism of such character that it may be actuated by various types of hand operated mechanisms and also
15 by various types of automatic operating devices.

A further object is to provide a construction which will give the swipe bar a straight line reciprocative movement instead of
20 swinging it in an arc.

Examples of preferred forms of constructions in which my invention may be embodied have been shown in the accompanying drawings and these will be hereinafter described. The especial novel features upon
25 which patent is desired will be defined in the claims.

Figure 1 is a face view of one form of my device shown in association with a portion
30 of a windshield.

Figure 2 is a face view, from the opposite side, of the base frame and the parts thereon.

Figure 3 is a section taken on the plane
3-3 as indicated on Figure 2.

Figures 4, 5, and 6 are face views of the base or frame and associated parts showing modified constructions, a covering or face plate of the base being removed in each case.

Figure 7 is a section on the line 7-7 of
40 Figure 6.

One of the characteristic features of my invention is the use of a straight line reciprocative movement and another is the use of a series of pivoted levers constrained to move in a symmetrical relation, for handling and controlling the swipe bar. Associated with such parts are the specific and novel mechanisms employed to actuate said levers and to insure their symmetrical movement.
45

50 My device is designed for mounting upon or along a margin of the glass which is to be kept clear of water. The most obvious and effective position upon or about a windshield is upon the upper frame bar of the
55 windshield. This is the position chosen for the accompanying illustration and the

position which will be hereinafter specifically described. It is, however, to be understood that mounting it in other positions is contemplated when and wherever such position seems advisable.
60

The operating parts are designed to be mounted in a self contained manner upon a base or frame 1 which conveniently contains spaced-apart plates, as 10, 11, and 12, 65 between, and supported upon which, are certain of the operating members.

The swipe bar 3 carries an ear, or ears, 30, upon which are pivoted by one end, swinging arms 20, which at their other ends are pivotally connected with other swinging arms 2. The arms 2, which for convenience I will call the first pair, are pivoted at 13, 13, upon the base or frame 1, at points which are separated while yet adjacent. These arms or
70 bars 2 extend beyond their pivots, such extended ends being engaged by an actuating member; the construction and operation of which parts being such as will effectively swing the arms, and also insure equal and
75 symmetrical angular swing as between the two arms.

In the construction shown in Figures 1, 2, and 3, the extensions of arms 2 beyond their pivots have laterally projecting pins 21
80 which enter slots 40 in a yoke 4, which is mounted in the base or frame so as to be confined to reciprocation in a definite path and to prevent any rocking or pivoting action. The manner shown for securing this
85 90 is to provide the yoke or plate 4 with two ears 41, which are bent at right angles, and pass through a guide slot 14 in plate 11.

The lugs or ears 41 are spaced apart and receive between them one end 50 of a bell
95 crank lever 5, pivoted at 51 upon the base. To the other end 52 is connected a wire or rod 53 by which the lever may be swung when desired from a distant point, either through the means of hand or power operated devices. A spring 54 may be used to return the parts to their normal position, which is with the swipe bar 3 raised close to
100 the base 1.

I have found the slot and pin a convenient means for connecting the operating member with the first pair of swinging arms 2. The slots may be in the connecting member, as shown in Figure 1, or in the arms, as shown in Figure 4. In the latter case, the
110 slots 22 are in the extensions of the arms beyond their pivots 13. In either case, I

prefer that the slot be curved, as is shown both in Figure 1 and in Figure 4.

Where the slot is in the arms, as in Figure 4, the intermediate member connecting the actuating lever 5 with the arms, becomes a pin, as 55, secured in the arm 50, and directly entering the slots 22.

In the construction shown in Figure 5, the ends of the arms 2 are bent, and the end 50 of the actuating lever is widened and provided with two rollers 56, which engage opposite sides of the curved or bent ends 23.

In the form shown in Figure 6, the adjacent ends of arms 2 are provided with a toothed arc, and between them is a rack bar 6, meshing with both, and mounted to slide in guides formed in, or carried by, the frame. The rack bar 6 is shown as having a pin 60, which enters a slot 57 in end 50 of the actuating lever 5.

To insure true movement of the swipe bar 3, means to insure its parallel position should be provided. Such means as illustrated consists in providing the ends of these arms 25 with intermeshing teeth 26.

To return the swipe bar to its uppermost position, the use of a spring is desirable. Preferably this should be contained in the assembly carried upon the frame 1, which 30 is done by a spring such as 54 shown. Various other types of springs and various other locations therefor may be employed.

I have not herein illustrated or described any specific means for actuating the mechanism, contemplating the use for this purpose of any one of several operating means, these including both hand and power operated devices.

It is believed that the manner of operation 40 of the device is clear without making a separate statement thereof.

While the above description has been worded to specifically apply to the use of the device upon the windshield of an automobile, this specific character is due solely to the fact that the drawings show such an application. It is evident that the device is equally applicable to the windows of street cars, locomotives, and in fact, all windows which are exposed to rain or moisture 45 which tends to cloud vision therethrough. It is therefore to be understood that, although the claims may refer to the invention as a wind shield swipe, or wiper, they are

not to be interpreted as limited to this use 55 alone, but to cover the device defined as used in any connection and for any purpose to which it is applicable.

What I claim as my invention is:

1. A window wiper comprising a base 60 member, two arms adjacently pivoted upon said base, two other arms pivoted one to the end of each of the first pair of arms, a wiper member pivoted upon the other ends of the second pair of arms, a yoke having vertical 65 guiding engagement with the base, and an operating engagement with the other ends of the first pair of arms.

2. A window wiper comprising a base 70 member adapted to be secured relative to the window, two arms adjacently pivoted upon said base, two other arms pivoted one to the swinging end of each of the first pair of arms, a wiper member pivoted upon the other ends of the second pair of arms, a yoke 75 having operating engagement with the adjacent ends of the first pair of arms, said yoke and the base member having guiding engagement preventing rocking of the yoke.

3. A window wiper comprising a base, two arms adjacently pivoted upon the base, a wiper member connected to the swinging arms to be operated thereby, a member having operative engagement with the adjacent ends of said arms, and guided for 85 movement so as to secure an equal and symmetrical angular swinging of the arms, and a lever for actuating said latter member.

4. A window wiper comprising a base, two arms adjacently pivoted upon said base, a second pair of arms pivoted upon the swinging ends of the first pair of arms, a wiper bar carried by the other ends of the second pair of arms, the outer ends of said second pair of arms having intermeshing 90 teeth insuring a continuous symmetrical swinging thereof, an operating lever pivoted upon the base, the base having a transversely positioned guide, and a connecting member 95 between the operating lever and the swinging arms having engagement with the said guide to control its direction of movement and position, said connecting member having a sliding engagement with the first pair of swinging arms.

Signed at Seattle, King County, Washington, this 8th day of March, 1926.

JAMES A. CARSON
